MACHINE FOR AFFIXING OPENING THREADS TO ENVELOPES

Application filed November 24, 1931. Serial No. 577,064.

This invention relates to improvements in machines for affixing opening threads to envelopes in order to facilitate removal of the contents thereof and more particularly the 5 invention is concerned with a machine of the type in which provision is made for incorporating the threads in the bodies of the envelopes during their formation from blanks.

A machine of the type generally described 10 includes means for applying an adhesive to predetermined areas of the blanks and means for delivering the blanks, after the application of the adhesive, to a folding mechanism in which the various flaps of the blank are 15 folded and secured after folding by the adhesive. It is the practice to secure the opening threads to the envelopes in the crease between those parts of the blank which constitute the front and back sides of the envelope, the threads being positioned adjacent 20 the joint between said parts before they are folded to the position in which they are secured by the adhesive.

The principal object of the present invention 25 is to provide a mechanism which is adaptable as an attachment to existing machines.

A further object is to provide a novel construction and arrangement of the parts of 30 the thread affixing mechanism whereby simplicity in construction and operation is obtained.

A still further object is a thread affixing 35 mechanism which is adapted to arrange the opening threads in such relation to those areas of the envelope blank to which the adhesive is applied that the threads are secured to the envelope by the adhesive, thereby avoiding 40 the necessity of impregnating or coating the threads with an adhesive.

The invention is illustrated in the accompanying drawings, in which:—

Figure 1 is a fragmentary view in elevation 45 of a machine in which the features of the invention are incorporated.

Figure 2 is a horizontal section taken along line 2—2 of Figure 1.

Figure 3 is a vertical section taken along 50 line 3—3 of Figure 1.

Figure 4 is a vertical section taken along line 4—4 of Figure 1.

Figure 5 is a vertical section taken along line 5—5 of Figure 1.

Figure 6 is an enlarged fragmentary sec- 55 tional view of the folder which carries the thread severing means, the said folder being shown in the position which corresponds to the inoperative position of the thread severing means.

Figure 7 is a similar view in which the folder is shown in the position which corresponds to the operative position of the thread severing means.

Figure 8 is a fragmentary view in plan of 65 the needle bar and co-operating parts of the thread affixing mechanism by which the thread is arranged for securement to the envelopes, the needle bar being shown in its retracted position.

Figure 9 is a vertical section taken along 70 line 9—9 of Figure 8.

Figure 10 is a similar view in which the needle bar is shown in its projected position in which the end of the thread is gripped by 75 a co-operating part of the mechanism.

Figure 11 is a similar view in which the needle is shown in its retracted position, the end of the thread still being gripped by the said co-operating part.

Figure 12 is an enlarged fragmentary view of the needle bar.

Figure 13 is a perspective view of a completely formed envelope, the ends of the opening thread being shown protruding beyond 85 the body of the envelope in order that they may be readily grasped during the opening operation.

The thread affixing mechanism, although 90 not so limited in use, is applicable to existing envelope folding machines which have been designed without contemplation of their use in connection with thread affixing mechanisms. The thread affixing mechanism, therefore, is illustrated, by way of example, in 95 connection with such a machine. The parts of the machine are mounted in a suitable frame which includes lower side frame members 15 and 16 and upper side frame members 17 and 18. A bed plate 19 is supported 100

upon the upper ends of the side frame members 15 and 16 beneath the lower ends of the side frame members 17 and 18.

The folding mechanism, as best shown in Figure 3, is carried by the bed plate 19. It includes a top plate 20 supported in spaced relation from the bed plate by brackets 21 and 21a at one end and a post 22 at the opposite end. The top plate 20 is formed with a rectangular opening 23 and as the blanks from which the envelopes are to be formed are positioned above the opening they are carried by a plunger 24 through it, during which operation those portions of the blanks which constitute the back sides, end flaps and sealing flaps of the envelopes are bent substantially at right-angles to those portions of the blanks which constitute the front sides of the envelopes. The plate 20 is also formed with front and side walls 25 and 26 respectively, all of which extend toward but terminate short of the bed plate 19. The walls 25 and 26 co-operate with a folder 27 in holding the bent portions of the blank against return to their original position so that they will co-operate in the desired manner with the various folders employed in the folding operations. The opening 23 is above an opening 28 formed in the bed plate 19, the latter opening being normally closed by a pivoted bottom plate 29. In addition to the folder 27, the folding mechanism also includes a pair of end folders 30 and 31 which operate in the openings between the bottom edges of the side walls 26 and the bed plate 19.

The folders 27, 30 and 31 bend those portions of the blank which are to be secured in a folded position by the adhesive which has been applied to the blank while the sealing flap of the envelope is creased by a folder 33, the latter operating beneath the lower edge 34 of the front wall 25.

In the arrangement of parts shown in Figure 3, the mechanism is conditioned to operate upon a blank B which has been arranged above the opening 23. As the plunger 24 moves downwardly, it engages that part of the blank which is to constitute the front side of the envelope and carries the latter through the opening 23 and arranges it upon the bottom plate 29. In this position, the flap 35 which is to form the back side of the envelope rests against the folder 27 while the two end flaps 36 rest against the end folders 30 and 31. The part 37 which is to provide the sealing flap of the envelope is held in its bent position by the front wall 25.

The blanks B are arranged beneath the plunger 24 by a slide 38. The latter includes a pair of bars 39 which fit in suitable guideways and which carry at their front ends a cross-piece 40, the latter being provided with an upwardly extending rib 41. The bars 39 carry brackets 42 at their rear ends which

are suitably connected by links 43 to power. The slide 38 is movable to a position beneath the adhesive applying elements 44 to receive a blank removed from the latter by a stripper plate 45. The blanks are carried upon a suitable table 46 arranged adjacent the top plate 20. The adhesive applying elements are arranged above the table 46 and are operated by a common rod 47, the said elements being adapted to apply an adhesive to the blanks in the usual manner.

The stripper plate 45 is formed with suitable openings 48 through which the elements are projected to apply an adhesive to the uppermost blank, it being understood that during such downward movement of the said elements the slide 38 is in a position to the left of that shown in Figure 3. The blank adheres to the elements and as they are moved upwardly by the rod 47, they carry the blank with them. As the blank is moved above the plane occupied by the slide 38 the latter is moved beneath the blank. Hence, as the elements pass through the openings 48, the blank falls upon the slide, the latter being in a position in which the rib 41 lies beyond the rear edge of the blank. The slide 38 is then operated to position the blank above the opening 23 and the plunger 24 operates to move the blank through the opening and down upon the pivoted bottom plate 29 in the manner described.

With the back side, end flaps and sealing flap held in the position to which they are bent, the end folders 30 and 31, back folder 27 and sealing flap folder 33 are operated in the order enumerated to complete the formation of the envelope by folding the initially bent parts. The end folders 30 and 31 are each connected by a link 49 to a bell crank 50. The latter is carried by a suitable bracket 51 secured to the underside of the bed plate 19. One arm 52 of the bell crank extends through a suitable opening formed in the bed plate and is pivotally connected to the link 49. The other arm 53 is connected by a rod 54 to a roller support 55. The roller 56 of the latter co-operates with a cam 57 which is mounted upon a main cam shaft 58. It will be apparent that the shaft 58 is adapted through the agency of the cams 57 to move the end folders 30 and 31 inwardly and downwardly upon the end flaps 36.

As the end folders return to their normal positions, the back folder 27 is adapted to fold the back side 35 of the envelope upon the two end flaps so that the former may be secured to the latter by the adhesive which has been applied to the back side over those areas which are to contact with the end flaps. In order to move the back folder 27 in the manner described, it is connected by a link 59 to an arm 60. The latter is fixed to a shaft 61 journalled in the brackets 21 and 21a. At the end of the shaft adjacent the bracket

21, the shaft 61 carries a crank 62, the free end of which is connected by a rod 63 to a roller carrying arm 64. The roller 65 carried by the said arm operates in a cam groove 66 formed in an element 67. The latter similarly to the cams 57 is mounted upon the main cam shaft 58. The roller carrying arm 64 is connected to the rod 63 by a sleeve 68 which is loosely mounted upon the rod 63 between a nut 69 and a spring 70. The latter acting against nuts 71 carried by the said rod, urges the sleeve 68 against the nut 69. The purpose of the spring 70 is to provide a resilient connection between the roller 65 and the rod 63 so that the back folder 27 will be resiliently urged against the bottom plate 29 during the folding operation. The element 67 is so arranged upon the cam shaft 58 that immediately after the end flaps of the envelope have been folded downwardly the back folder 27 is operated to fold the back side of the envelope upon the flaps, whereby the body of the envelope is completed. During the return movement of the back folder 27 the sealing flap folder 33 is operated to form a crease in the blank between the body and sealing flap of the envelope. The bottom plate 29 is then lowered by a rod 72 to permit the discharge of the completed envelope from the folding mechanism, the practice being to deliver the envelopes as completed to a suitable drying conveyor.

In accordance with the invention means, operating in timed relation with the various folders, is provided for arranging an opening thread adjacent the joint between the back side of 35 of the envelope and the front side 35a prior to the operation of the folder 27. The said means, as illustrated, includes the needle bar 73 which is carried by a rod 74. The latter is mounted for movement in the direction of its length in blocks 75 suitably carried by the frame-work of the machine. The rod 74 is connected by a pin 76 to a bell crank 77 which is suitably supported by the side frame member 15. The pin 76 extends through a slot 78 formed in one arm 79 of the bell crank and the other arm 80 of the latter is connected by a link 81 to an arm 82 (see Figure 4) which is pivotally connected at one end to a bracket 83 carried by the frame-work of the machine. The arm 82 carries a roller 84 which co-operates with a cam 85. The latter is mounted upon an auxiliary cam shaft 86 which is driven from the main cam shaft 58 through the medium of gears 87 and 87a. The cam 85 operates in such timed relation with the cams 57 that the needle bar 73 moves across the back of the front side of the envelope adjacent the joint between the said side and the back side 35 and returns to its retracted position prior to the operation of the folder 27.

The needle bar 73 carries a spring clip 73a (see Figure 12) and a continuous length of

thread 88 passes from a suitable spool through eyelets 89 and from the eyelets between the bar and the clip 73a, whereby the thread is frictionally engaged. The end of the thread 88 extends beyond the terminal portions of the bar and clips 73 and 73a respectively, as shown. It will be apparent, therefore, that as the needle bar 73 moves over the front side of the envelope it carries the thread 88 with it.

Means is provided, as the needle bar 73 reaches a projected position in which the thread 88 extends entirely across and beyond the margins of the front side of the envelope, for gripping the end of the thread so that as the needle bar returns to its retracted position it slips over the thread. The latter remains in its position across the envelope adjacent the joint between the front and back sides. The said means includes a pair of fingers 90 and 91, both of which are freely mounted upon a stub shaft 92 carried by the bracket 21a. The finger 90 is formed with a shoulder 93 which co-operates with a pin 94 carried by the stub shaft. A spring 95 is carried upon the stub shaft, one end of the spring being secured to the latter and the other end being secured to the finger 90. The spring 95 acts against the finger 90 tending to move in angularly about said shaft, the shoulder 93 preventing movement of the finger 90 past the point at which the shoulder 93 engages the pin 94. The finger 91 on the other hand is pivotally connected by a rod 96 to an arm 97. The latter is pivotally connected at one end to a bracket 98 carried by the frame-work of the machine. The arm 97 carries a roller 99 which co-operates with a cam 100, the said cam being mounted upon the auxiliary cam shaft 86. The cam 100 operates in timed relation to the cam 95 so that as the needle bar 73 approaches the fingers 90 and 91 they are in the position shown in Figure 9, that is to say, open. While in this position, that portion of the thread which extends beyond the end of the needle bar is moved by the latter between the two fingers, at which time the cam 100 causes the finger 91 to move downwardly into co-operating relation with the finger 90, thereby to engage the projecting end of the thread. As the finger 91 continues downwardly a short distance further, it carries with it the finger 90 against the action of the spring 95. While the thread is thus engaged,

the needle bar returns to its retracted position whereby a portion of thread is supported between the latter and the gripping fingers adjacent the crease between the front and back sides of the envelope. Hence, as the folders 27 are operated to fold the back side upon the front side, the thread is pressed between the two sides. In this connection it is to be noted that in the adhesive applying operation the adhesive, as indicated in dotted lines, in Figure 13, is preferably extended to

the crease 101 of the envelope so that as the thread is squeezed between the back and front sides of the latter it adheres to portions of the envelope body to which the adhesive has been applied. The adhesive, therefore, which has been applied to the back side 35 serves to secure the thread to the body of the envelope in such a manner that when the protruding end 102 is grasped and pulled it will not become unanchored so as to slip lengthwise from between the fold provided by the back and front sides.

In order to sever that portion of the thread 88 which is to be affixed to the envelope, the folder 27, as best shown in Figures 6 and 7, carries a blade 103. The latter co-operates with a fixed blade 104 carried by the bed plate 19. As the folder 27 is moved downwardly to fold the back side 35 upon the front side 35a of the envelope, the blade 103 co-operates with the blade 104 to sever the thread 88 at a point between the end of the envelope body and the end of the needle bar 73, thereby leaving a portion of the thread 88 extending beyond the needle bar 73. Hence, in the next forward movement of the latter the protruding end of the thread will be gripped between the fingers 90 and 91 in the manner described.

From the foregoing, it will be apparent that the thread affixing mechanism is adapted to arrange a thread adjacent to the joint between the back and front sides of the envelope so that as the former is folded upon the latter the thread is incorporated in the body of the envelope, the adhesive which is availed of to secure the back side to the end flaps of the envelope being utilized to secure the thread to the envelope. Hence, there is no necessity for the application of an adhesive to the thread. The mechanism has the further advantage that it may be applied to existing machines which have been designed for the folding of blanks into envelopes but which have not contemplated the use in connection therewith of mechanisms for affixing opening threads to the envelopes. The various parts of the mechanism are controlled by the main cam shaft which operates the movable parts of the folding mechanism and hence the thread affixing mechanism co-operates with the folding mechanism to arrange the threads relative to the blanks accurately and rapidly without the necessity of varying the manner of operation of the folding mechanism.

I claim as my invention:

1. The combination with an envelope folding mechanism having a member movable to fold one part of an envelope blank upon another part thereof, of a reciprocating member adapted to carry a portion of a continuous length of thread across the envelope blank in front of said movable member and adjacent the joint between said parts, means for gripping said thread to hold the latter in such

position during the return movement of said reciprocating member, whereby said first mentioned part may be folded upon said portion of thread during the operation of said movable member and means for severing said portion of thread from the remainder of said continuous length of thread. 70

2. The combination with an envelope folding mechanism having a member movable to fold one part of an envelope blank upon another part thereof, of a reciprocating member adapted to carry a portion of a continuous thread across the envelope blank in front of said movable member adjacent the joint between said parts, gripping members between which said thread is positioned, means for operating said gripping members to hold said thread against movement during the return movement of said reciprocating member, whereby said first mentioned part may be folded upon said portion of thread during the operation of said movable member and means for severing said portion of thread from the remainder of said continuous length of thread. 75 80 85 90

3. The combination with an envelope folding mechanism having a member movable to fold one part of an envelope blank upon another part thereof, of a reciprocating member adapted to carry a portion of a continuous length of thread across the envelope blank in front of said movable member adjacent the joint between said parts, gripping members between which said thread is positioned, means for operating said gripping members to hold said thread against movement during the return movement of said reciprocating member, whereby said first mentioned part may be folded upon said portion of thread during the operation of said movable member and means for severing said portion of thread from the remainder of said continuous length of thread, said gripping means being adapted to release said thread upon completion of the return movement of said reciprocating member. 95 100 105 110 115

4. The combination with an envelope folding mechanism having a member movable to fold one part of an envelope upon another part thereof, of a reciprocating member adapted to carry a portion of a continuous length of thread across the envelope blank in front of said movable member and adjacent the joint between said parts, means for gripping said thread so as to hold the latter in such position during the return movement of said reciprocating member, whereby said first mentioned part is folded upon said portion of thread during the operation of said movable member and means for severing said portion of thread from the remainder of said continuous length of thread, said means last mentioned being adapted to leave a portion of said remainder protruding from said member so that said end may be gripped by said grip- 120 125 130

ping means when said reciprocating member moves across the succeeding blank.

5. The combination with an envelope folding mechanism having a movable member for folding one part of an envelope blank upon another part thereof, a cam shaft and means connecting said cam shaft with said movable member for operating the latter, of a reciprocating member adapted to carry a portion of a continuous length of thread across the envelope blank in front of said movable member and adjacent the joint between said parts, means connecting said reciprocating member with said cam shaft for operating said member in timed relation with said movable member, means for gripping said thread when said reciprocating member is in its projected position to hold said thread against movement during the return movement of said reciprocating member, whereby said first mentioned part may be folded upon said portion of thread during the operation of said movable member and means for severing said portion of thread from the remainder of said continuous length of thread.

6. The combination with an envelope folding mechanism having a pivoted member for folding one part of an envelope blank upon another part thereof, a cam shaft and means connecting said cam shaft with said pivoted member for operating the latter, of a reciprocating member adapted to carry a portion of a continuous length of thread across the envelope blank in front of said pivoted member and adjacent the joint between said parts, a second cam shaft operated in timed relation to said first mentioned cam shaft, means connecting said second cam shaft with said reciprocating member for operating the latter, means for gripping said thread when said reciprocating member is in its projected position so as to hold said thread against movement during the return movement of said reciprocating member, whereby said first mentioned part may be folded upon said portion of thread during the operation of said movable member and means for severing said portion of thread from the remainder of said continuous length of thread.

7. The combination with an envelope folding mechanism having a pivoted member for folding one part of an envelope blank upon another part thereof, a cam shaft and means connecting said cam shaft with said pivoted member for operating the latter, of a reciprocating member adapted to carry a portion of a continuous length of thread across the envelope blank in front of said pivoted member and adjacent the joint between said parts, a second cam shaft operatively connected to said first mentioned cam shaft, means connecting said second cam shaft with said reciprocating member for operating the latter, means for gripping said thread when said reciprocating member is in its projected posi-

tion so as to hold said thread against movement during the return movement of said reciprocating member, whereby said first mentioned part may be folded upon said portion of thread during the operation of said movable member and means for severing said portion of thread from the remainder of said continuous length of thread, said gripping means being connected to and operated by said second cam shaft.

8. The combination with an envelope folding mechanism having a pivoted member for folding one part of an envelope blank upon another part thereof, a cam shaft and means connecting said cam shaft with said pivoted member for operating the latter, of a reciprocating member adapted to carry a portion of a continuous length of thread across the envelope blank in front of said pivoted member and adjacent the joint between said parts, gripping members between which said thread is positioned, a second cam shaft operatively connected to said first mentioned cam shaft and to said member for operating the latter to grip said thread and hold the latter against movement during the return movement of said reciprocating member, whereby said first mentioned part may be folded upon said portion of thread during the operation of said pivoted member and means for severing said portion of thread from the remainder of said continuous length of thread upon completion of the return movement of said reciprocating member.

9. The combination with an envelope folding mechanism having a pivoted member for folding one part of an envelope blank upon another part thereof, a cam shaft and means operatively connecting said cam shaft with said pivoted member for operating the latter, of a reciprocating member adapted to carry a portion of a continuous length of thread across the envelope blank in front of said pivoted member and adjacent the joint between said parts, gripping members between which the said thread is positioned, a second cam shaft operatively connected to said first mentioned cam shaft and to said members for operating the latter to grip said thread and hold the latter against movement during the return movement of said reciprocating member, whereby said first mentioned part may be folded upon said portion of said thread during the operation of said pivoted member and means for severing said portion of thread from the remainder of the continuous length of thread, said gripping members being adapted to release said thread upon completion of the return movement of said reciprocating member.

10. The combination with an envelope folding mechanism having a movable member for folding one part of an envelope blank upon another part thereof, of a reciprocating member adapted to carry a portion of a

continuous length of thread across the envelope blank in front of said member and adjacent the joint between said parts and means for gripping the end of said thread so as to 5 hold the latter in such position during the return movement of said reciprocating member, whereby said first mentioned part may be folded upon said portion of said thread during the operation of said movable member, said means including a finger resiliently held against movement, a companion finger which co-operates with said finger first mentioned and means for moving said companion finger toward said first mentioned finger to 10 grip said thread and means for severing said portion of thread from the remainder of the continuous length of thread.

11. The combination with an envelope folding mechanism having a pivoted member 20 for folding one part of an envelope blank upon another part thereof, of a reciprocating member adapted to carry a portion of a continuous length of thread across the envelope blank in front of said member and adjacent the joint between said parts, means for gripping the end of said thread so as to hold the latter in such position during the return movement of said reciprocating member, whereby said first mentioned part may be 25 folded upon said portion of thread during the operation of said pivoted member, said means including a support, a finger pivotally mounted on said support, means resiliently resisting movement of said finger in one direction, 30 a second finger pivotally mounted on said support and co-operating with said first mentioned finger and means for moving said second finger toward said first mentioned finger to grip said thread, thereby moving said first 35 mentioned finger against the action of said resilient means and means for severing said portion of thread from the remainder of the continuous length of thread.

12. The combination with an envelope 45 folding mechanism having a pivoted member for folding one part of an envelope blank upon another part thereof, a cam shaft and means connecting said cam shaft with said pivoted member for operating the latter, of 50 a reciprocating member adapted to carry a portion of a continuous length of thread across the envelope blank in front of said pivoted member and adjacent the joint between said parts and means for gripping said 55 thread to hold the latter in such position during the return movement of said reciprocating member, whereby said first mentioned part may be folded upon said portion of said thread, during the operation of said pivoted 60 member, said means including a support, a finger pivotally mounted upon said support, means for resiliently resisting angular movement in one direction of said finger, a second finger pivotally mounted upon said support, 65 a second cam shaft operatively connected to

said first mentioned cam shaft and to said second finger for moving the latter toward said first mentioned finger against the action of said resilient means to grip said thread and means for severing said portion of thread 70 from the remainder of the continuous length of thread.

13. The combination with an envelope folding mechanism having a movable member 75 for folding one part of an envelope blank upon another part thereof, a cam shaft and means operatively connecting said cam shaft with said movable member, of a reciprocating member adapted to carry a portion of a continuous thread across the envelope blank and position it in front of said movable member adjacent the joint between said parts, means for gripping said thread to hold it in such position during the return movement of said reciprocating member, whereby said first mentioned part may be folded upon said 80 thread during the operation of said movable member, and means connecting said last named means to said cam shaft, whereby the thread is positioned in the manner described 85 prior to the operation of said movable member.

14. The combination with an envelope folding mechanism having a movable member for folding one part of an envelope upon another part thereof, a cam shaft and means operatively connecting said cam shaft with said movable member, of means for positioning a thread in front of said movable member adjacent the joint between said parts, a second cam shaft, means operatively connecting said cam shafts and means operatively connecting said second cam shaft to said means first mentioned, whereby the thread is positioned 90 in the manner described prior to the operation of said movable member.

15. The combination with an envelope folding mechanism having a movable member for folding one part of an envelope blank upon another part thereof, a cam shaft and means operatively connecting said cam shaft with said movable member, of means for carrying a portion of a continuous length of thread across the envelope blank in front of said movable member adjacent the joint between said parts, means for gripping said thread so that the latter is held in such position during the return movement of said thread carrying means, whereby the movable member may be operated to fold said first mentioned part upon said portion of thread, a second cam shaft operatively connected to said first mentioned cam shaft, means operatively connecting said thread carrying means and said gripping means to said second cam shaft and means for severing said portion of thread from the remainder of the continuous length of thread.

16. The combination with an envelope folding mechanism having a member movable to 130

fold one part of an envelope blank upon another part thereof, of a reciprocating member adapted to frictionally engage a portion of a continuous length of thread and carrying it across the envelope blank in front of said movable member adjacent the joint between said parts, means for gripping said thread so as to hold said portion in such position during the return movement of said reciprocating member, whereby said first mentioned part may be folded upon said portion of thread during the operation of said movable member and means for severing said portion of thread from the remainder of the continuous length of thread.

17. The combination with an envelope folding mechanism having a member movable to fold one part of an envelope blank upon another part thereof, of a reciprocating member adapted to frictionally engage a portion of a continuous length of thread and carry it across the envelope blank in front of said movable member adjacent the joint between said parts, gripping members between which said thread is positioned, means for operating said gripping members to hold said portion of thread against movement during the return movement of said reciprocating member, whereby said first mentioned part may be folded upon said portion of thread during the operation of said movable member and means for severing said portion of thread from the remainder of the continuous length of thread.

25 In testimony whereof I affix my signature.

CLARENCE N. FULLER.
